COOKING RANGE UNIT

William J. Miller, Galesburg, Ill.

Application February 20, 1956, Serial No. 40,218

Term of patent 3½ years

(Cl. D81—4)

FIG. 4

FIG. 5

Fig. 1 is a perspective view of a cooking range unit embodying my new design, the side of the unit not shown being plain;

Fig. 2 is a section on the line 2—2 of Fig. 1;

Fig. 3 is a sectional view taken on line 3—3 of Fig. 1;

Fig. 4 is an enlarged fragmentary perspective view of the upper control panel of Fig. 1; and

Fig. 5 is an enlarged fragmentary perspective view of the lower control panel of Fig. 1.

The dominant features of my design reside in the portions illustrated by solid lines.

I claim:

The ornamental design for a cooking range unit, as shown and described.
